UNITED STATES PATENT OFFICE.

ARTHUR H. MAYNARD, OF WARWICK, RHODE ISLAND, ASSIGNOR TO BOSTON WIRE STITCHER COMPANY, OF EAST GREENWICH, RHODE ISLAND, A CORPORATION OF MAINE.

STAPLING MACHINE.

Application filed June 10, 1922. Serial No. 567,303.

This invention relates to improvements in stapling-machines for fastening together sheets of paper or the like.

One object of the improvement is to provide a light, compact machine suitable for use as an office or desk appliance.

Another object of the improvement is to render the device more convenient of operation, more efficient in use, and proof against derangement or getting out of order.

Another object of the improvement is to provide for the automatic feeding of the staples to the work without liability of their becoming jammed or bent and causing clogging of the machine.

Another object of the improvement is to simplify the mechanism of the machine, while reducing its cost of manufacture and rendering it more staunch and durable in use.

Further objects of the improvement are set forth in the following specification which describes a preferred embodiment of the invention as illustrated by the accompanying drawings.

In the drawings:

Fig. 1 is a side elevation of my improved stapling-machine showing its upper stapling-member or arm in its normal, raised position to adapt the work to be inserted therebeneath;

Fig. 2, a vertical sectional view of the same taken on a medial, longitudinal plane and illustrating the stapling-arm depressed against the work;

Fig. 3, a front view of the device showing its lower portion partly in section on the line 3—3 of Fig. 1, and illustrating the stapling-arm in its raised position;

Fig. 4, a similar view showing the arm and its staple-driver in depressed position at the finish of the operation of clinching the staple through the work;

Fig. 5, a plan view of the stapling-arm showing the rearward end of its staple-magazine partly in section;

Fig. 6, a detailed view of the forward end of the arm showing the guiding-slots for the staple-driver;

Fig. 7, a perspective view of the staple-pusher which slides the staples through the magazine, with the impeller-spring for the pusher indicated by dash lines;

Fig. 8, an enlarged perspective view of the

holding- or anchoring-device for the pusher 55 impeller-spring;

Fig. 9, an enlarged cross-sectional view of the staple magazine taken on the line 9—9 of Fig. 2; and

Fig. 10, an enlarged perspective view of 60 the lower portion of the staple-driver showing the manner in which it engages the top of the staple.

Referring first to Figs. 1 and 2 of the drawings, my improved stapling-machine 65 comprises, in general, a flat base 2 designed to rest on the desk, table or other support, and an upper stapling-member or arm 3 hinged to the rearward end of the base to adapt it to be pressed down against the work 70 which is placed beneath its forward end. The arm 3 serves as a magazine for holding a supply of wire staples 8, and mounted on its forward end is the staple-driving means 75 which cooperate with the clincher-device at the front of the base 2.

For the sake of economy in cost of manufacture and reduction in weight, the base 2 is preferably constructed from sheet-metal in the form of a flat strip, see Figs. 1, 2 80 and 3. Adjacent its rearward end the strip is cut away or punched out to form a rectangular opening 4 having integral ears 5 projecting from its sides. The ears 5 are bent upwardly at right-angles to the main strip to provide two parallel spaced-apart hinge-portions, see Fig. 3, adapted to receive the cross-pin 6 which serves as a pivot for the arm 3.

As shown in Figs. 1, 2, 5 and 9, the arm 90 3 is also preferably constructed of sheet-metal and comprises two opposite parallel side-plates 7 which are held in spaced-apart relation by a plurality of cross-pins or rivets 8. The plates 7 are of angular form in cross-section, having upper, marginal flanges 9 formed by bending over the metal at right-angles along the top. The edges of the flanges 9 are spaced apart to provide a slot 10 or guideway in which the impeller-spring 100 11 of the staple-pusher 12 slides.

Positioned between the sides of the arm 3 is a core or lining-strip 15 of substantially inverted U-shape or trough-form which serves as a track or support for the staples 8 straddling its top, see Figs. 5 and 9. The core 15 is constructed from sheet-metal of somewhat lighter stock than that of the

side-plates 7, being conveniently formed or struck up in a punch-press. Referring to Fig. 9, the upper portion of the core 15 is of slightly less width than the space between 5 the side-plates 7 of the arm 3, but at the bottom its sides are offset to adapt them to abut the inner faces of the plates. The rivets 8, previously referred to, are inserted through the sides of the arm 3 and through 10 the core or staple-support 15 with an enlarged sleeve or hub 18 surrounding their central portions between the offset sides of the core. The ends of the hub 18 are thus caused to hold the sides of the core or support 15 against the side-plates 7 of the arm 3 so that when the rivets 8 are headed over on their ends, as shown in Fig. 9, the several parts are tied together and braced at the center to provide a staunch, rigid structure. 15

It will also be observed from Fig. 9 that the sides of the upper portion of the core 15 are maintained in spaced relation with the inner faces of the side-plates 7 of the arm 3 whereby to provide two relatively deep, narrow slots in which the legs of the staples 8 slide. The top of the core or support 15 is preferably recessed with a concavity 19 extending throughout substantially its whole length, the staples 8 being thus caused to rest 20 on the core at the two outside points only, whereby the frictional resistance to the sliding-movement of the staples is materially reduced. As shown in Figs. 1 and 2, three pins or rivets 8 are employed as struts for 25 the side-plates 7 of the arm 3, while a fourth pivot-pin 6, previously mentioned, fits loosely in holes in the side-plates with its ends received in suitable holes in the hinge-ears 5 on the base 2.

At the forward end of the arm 3 are two upright arms 22 formed integral with the side-plates 7. As shown in Fig. 5, the uprights 22 form extensions of the top-flanges 9 on the plates 7, being bent at right-angles 30 thereto and spaced apart at a distance equal to the width of the slot 10 between the edges of the flanges. The uprights 22 are tied together at the top by a rivet 23 which has an enlarged body or hub 24, see Fig. 2, disposed with its ends abutting the inner faces 35 of the uprights. At the front of the uprights 22 are two ears or extensions 25 bent outwardly at an angle and then curled inwardly at their ends to provide two opposite, vertical ways or guiding-tracks 26 on which the staple-driver 30 slides. 40

Referring to Figs. 2, 3, 4 and 10, the staple-driver 30 consists of a rectangular slide which, to save machining operations, is 45 preferably constructed of two flat, overlying plates 27 and 28 riveted together, as shown in Fig. 10. The forward plate 27 may be made of relatively soft metal, while the rearward plate 28 is of hardened steel and of 50 slightly greater width so that its edges pro-

ject beyond the sides of the forward plate to provide vertical splines or fins 31 which overlap the guiding-tracks 26 at the front of the uprights 22. The splines 31 are further adapted to slide in grooves 32 formed 70 at the front of the arm 3 by bending the side-plates 7 around into spaced relation to the forward edges of the flanges 9, see Fig. 6.

Mounted on the upper end of the driver 30 is a presser or hand-knob 33 which is preferably constructed of sheet-metal in the novel form illustrated in Figs. 1, 2 and 3. As shown in these views, the knob 33 has a slightly convex, circular top with a depending skirt or flange 34 overhanging its rim. 75 At the front of the knob the metal of its rim 34 is continued inwardly in a curved strip 35 which is then bent downwardly to form a flat extension or front-plate 36. The extension or plate 36 is adapted to fit against the front face of the driver 30 with the under side of the cap or knob 33 resting on the upper edge of the driver, see Fig. 2. A rivet 37 secures the knob 33 to the driver 30 in this relation and the two parts are thus arranged to operate as a unit. Bent around from the front-plate 36 of the knob 33 are two rearwardly projecting side-strips or wings 38 which are extended upwardly in the arms 39, see Figs. 1 and 4. The upper ends of the arms 39 abut the under side of the knob 33 and thus serve as a further support or reinforcement for stiffening the whole structure. It will also be noted by reference to Fig. 5 that the front-plate 36 and its wings 38 conform to the curved ends of the ears 25 whereby they serve as a guiding means for holding the driver 30 in place on the vertical ways or tracks 26 on which it slides. 100

The knob 33 is normally held in raised position above the arm 22, to maintain the driver in elevated relation to the staples, by means of a helical spring 40. As shown in Fig. 2, the spring 40 bears on the underside of the knob 33 and is pocketed in a tube or socket 41. The socket 41 consists simply of a cartridge-shaped shell formed with a flange 42 surrounding its upper rim. It is mounted on the uprights 22 by simply inserting it between the angular extensions or ears 25 with its flange 42 resting on the upper edges thereof. As shown in Figs. 2 and 5, one side of the flange 42 is cut away or flattened off at 43 to allow the driver 30 to slide up and down against it. At the bottom of the front-plate 36 of the knob 33 are two lugs or stops 44 bent around at the sides to adapt them to contact with the lower edges of the ears 25 to limit the upward movement of the knob. In this way the knob 33 is prevented from being forced off from its guideways under the action of the spring 40 and the upward stroke of the driver 30 is controlled within defined limits. 105 110 115 120 125 130

The pusher 12 which feeds the staples *s* through the magazine in the arm 3, to bring them successively into position beneath the staple-driver 30, is arranged to slide on the 5 core 15. As shown most clearly in Fig. 7, the pusher 12 is preferably constructed from a strip of relatively thin sheet-metal with its sides bent down to form runners 46 adapted to straddle the core 15 and slide within the 10 side-plates 7 of the arm 3 with the flanges 9 overlying its top. Bent up from the rearward end of the pusher 12 is a T-shaped finger-piece 47 which provides a grip for sliding the pusher back against the force of 15 its impeller-spring 11 whereby it may be withdrawn from the magazine to permit the loading of the latter with staples. The finger-piece 47 also serves as a stop for contacting with the rearward edges of the 20 uprights 22 to limit the forward sliding movement of the pusher under the action of its impeller-spring 11.

Referring to Fig. 2, the impeller-spring 11 consists in a flat strip or ribbon of tempered metal which is wound into a volute coil 48. The outer free end of the spring 11 is attached to the top of the pusher 12, as shown in Fig. 5. Referring to Fig. 6, the pusher is slotted across its top to form two 30 straps 50 which are arched upwardly to permit the end of the spring 11 to be inserted thereunder, as indicated by the dotted lines in this view. The edges of the spring 11 are formed with pairs of opposite notches 51, 35 see Fig. 1, and after the spring has been slipped into place beneath the straps 50 the latter are "smashed" or flattened down by a blow from a hammer, or in a press, so that the ends of the straps will engage with the 40 notches, as shown in section in Fig. 5. In this manner the end of the spring 11 is securely anchored to the pusher 12 without the use of pins, screws, rivets or other separate means.

45 The coiled end 48 of the spring 11 is held between the uprights 22 on the arm 3 by means of a novel and ingenious form of mounting as next described. Referring to Fig. 8, this mounting or anchorage for the 50 spring 11 comprises simply a hub or barrel 55 formed by bending a strip of sheet-metal into a tube with one end of the strip bisecting its interior in the flat portion 56. The opposite end of the strip is narrowed at 55 57 by cutting away its sides to form the opposite shoulders 58. The end of the narrowed portion 57 of the strip is spaced slightly apart from the inwardly bent flat portion 56 to provide an opening 59 to allow 60 the end of the spring 11 to be introduced therethrough. Referring to Fig. 2, the inner end of the coil 48 of the spring 11 is folded back on itself at 60 to provide a stop or abutment adapted to seat against the 65 lower edge of the flat, diametrically-disposed

cross-strip 56 in the hub 55. In applying the spring 11 to the hub 55 the latter is inserted axially through the coil 48 with the inner end of the spring passing through the opening 59 and down in under the cross-strip 56. The coil 48 is thus held on the hub 55 with its end abutment 60 anchored under the edge of the strip 56, and being thus maintained under tension it will normally 70 tend to wind itself up.

75 Referring to Fig. 1, the hub 55 is held in notches on the forward edges of the uprights 22 on the arm 3. Each upright is notched with a stepped opening 62 forming a recess with a shoulder 63 against which the cross-strip 56 in the hub 55 bears, and a deeper, quadrant-shaped cut 64 in which the under curved side of the hub seats. The narrowed portion 57 of the hub 55 is received in the space between the inner faces 80 of the uprights 22 with its shoulders 58 abutting the edges 65 of the notches 62. In this manner the hub 55 is securely held in place in the notches 62 under the pull on the free end of the spring 11, while also 85 being prevented from turning so that the spring is maintained under tension to adapt it to wind itself up to draw the pusher 12 along the arm 3.

90 As before mentioned, the clincher-means or anvil 70 for bending over the legs of the staples *s* is located at the forward end of the base 2. As illustrated in Figs. 2, 3 and 4, the anvil 70 may consist of a block of hardened metal inserted in a slot or opening 71 95 in the base 2 and provided with end abutments or flanges 72 for holding it in place. The upper face of the anvil 70 is formed with grooves 73 for receiving the legs of the staples *s*, see Fig. 4, and the bottoms of 100 the grooves are preferably of arcuate shape whereby they tend to bend the legs of the staples inwardly toward each other while forcing their points upwardly to set the wire 105 to insure a firm clinch.

110 The arm 3 is maintained normally in its raised position, as shown in Fig. 1, by means of a flat spring 75 secured to the base 2. Referring to Fig. 2, a stud or projection 76 is struck up from the top of the base 2 by indenting its underside at 77. The projection 76 serves as an anchorage for the end of the spring 75 which is pierced with a hole 78 for receiving the projection. From this anchorage the spring 75 extends in under the pivot-pin 6, the latter being provided with a shouldered groove 79 on its periphery with which the edges of the spring engage. The spring 75 thus has an added function to restrain the pin 6 from axial movement to hold it in place in the hinge-ears 5 while permitting its convenient removal when required. The spring 75 is bent upwardly to adapt its free end to rest on the top of the central hub 120 125 130 135 of the end rivet 8 which extends between

the side-plates 7 of the arm 3. The tension of the spring 75 causes it to bear on the pin 6 to exert a downward pressure on the rivet 8 to tilt the forward end of the arm 3 upwardly until its rearward end strikes the top of the base 2, as shown in Fig. 1. When the arm 3 is pressed downwardly the spring 75 flexes between its terminals, as shown in Fig. 2.

Having now described in detail the preferred structure and arrangement of the parts of my improved device its method of operation will next be explained: The staples *s* for use in the machine are made from relatively fine wire bent into U-shape of a width to adapt them to straddle the core 15 in the magazine on the arm 3. Staples of this type form a well known commodity and are usually put up in commercial packages or "sticks" as they are termed. Each package or stick contains a large number of staples, in some cases just sufficient staples for one loading of the magazine, which are assembled on a strip of wood or metal and held in place by a binder of paper, cord, or a metal strap. A preferred form of stick consists of a thin metal strip bent into a rectangular tube with the staples straddling its sides and held in alinement by a metal band extending along its top. In charging or loading the machine the end of the stick is rested on the end of the core 15 which is provided with a tab or tail 80 projecting rearwardly from the end of the arm 3. The tie or strap which holds the staples on the stick is released and the staples may then be slid into the magazine; it being understood, of course, that the staple-pusher 12 is first removed from the magazine by sliding it rearwardly off from the core 15.

After the magazine has been charged with the staples *s* the pusher 12 is replaced in its rearward end by inserting it under the flanges 9 on the side-plates 7 of the arm 3 with its runners 46 straddling the core 15, see Figs. 2 and 5. In applying the pusher 12 to the magazine its impeller-spring 11 is drawn back against the inherent tension of the coil 48 so that the latter will have a constant tendency to draw the pusher forward on the arm 3. The pusher 12 is thus caused to force the row of staples *s* forward in the magazine until the foremost one brings up against the bent-over ends of the side-plates 7 which form the grooves 32 on the arm 3, see Figs. 3 and 6. It will be observed by reference to Figs. 2 and 5 that the staples *s* slide on the core 15 under the overlying side flanges 9, whereby they are prevented from rising up out of alinement or becoming displaced from position.

To insert a staple through the work the sheets or pages *p* to be fastened together are placed above the anvil 70 on the base 2, see Fig. 2, and the operator then presses down

on the knob 33. The spring 75 which normally holds the arm 3 raised above the base 2 has considerably less tension than the spring 40 under the knob 33 so that the first pressure on the knob will carry the arm down against the sheets *p* to hold them in place while the staple is being applied thereto. After the arm 3 has been carried down against the work in this manner the continued pressure on the knob 33 will cause the driver 30 to slide downwardly on its tracks or guideways 26 to act on the staple *s*. Normally the staple-driver 30 is held in elevated position by the spring 40, with its lower recessed edge just above the top of the leading staple *s*, as shown in Figs. 1 and 3. As the driver 30 slides downwardly its lower edge engages the top of the staple *s* in the manner illustrated in Fig. 10. The staple will thus be forced downwardly with its legs guided in the slots or grooves 32 between the forward edges of the sides of the core 15 and the bent-over ends of the side-plates 7, see Figs. 2, 3 and 6. The legs of the staple *s* will be driven through the several thicknesses of paper *p*, and impinging upon the bottom of the grooves 73 in the top of the anvil 70 will be bent inwardly and clinched over as shown in Fig. 4. After the staple has been driven through the work and clinched against the underside thereof in this manner the knob 33 is released and its spring 40 returns it to raised position while the arm 3 is also elevated by the spring 75, the parts being thus returned to first position, as shown in Fig. 1. As the lower edge of the staple-driver 30 is elevated above the top of the core 15 the stops 44 on the plate 36 of the knob 33 strike against the lower edges of the ears 25 to prevent its further movement. Immediately the driver 30 is raised to this position the pusher 12 is drawn forward under the tension of its spring 11 to push the staples forward to bring the next leading one under the edge of the driver in position to be driven through the work at the next operation. In this way the staples are successively fed forward after each stroke of the driver so that the feed is automatic and continuous until the supply of staples in the magazine is exhausted. After the last staple has been used the pusher 12 is drawn back to the end of the arm 3 and lifted out of its guideway, when a new charge of staples may be slid into the magazine in the manner as previously explained.

It will be observed that my invention provides a particularly light-weight, simple, compact and efficient device which is convenient and durable in use for the purpose specified. My improved machine may be constructed from sheet-metal stampings, which provides for economy in cost of manufacture; and the elimination of machined parts, such as screws, studs and the like,

further reduces the manufacturing cost. Moreover, the parts of the device are more easily and quickly assembled and less liable to derangement or getting out of order.

- 5 While I have herein illustrated and described one preferred embodiment of my improvements it is to be understood that various modifications may be made in the structure and arrangement of the parts of the device without departing from the spirit or 10 scope of the invention; therefore, without limiting myself in this respect, I claim:

1. In a stapling-machine, the combination of a staple-carrying arm having divergent 15 ears at its forward end, a socket inserted between said ears to seat thereagainst, a staple-driver slidably mounted on the arm at the front of the socket and bearing thereagainst to hold said socket in place between 20 the ears on the arm, and a spring pocketed in said socket and arranged to act on the driver to maintain the latter in raised position while adapting it to be slid downwardly to operate on the staples.

25 2. In a stapling-machine, the combination of a base, an arm mounted above the base and comprising side-plates having parallel uprights at their ends with ears projecting forwardly therefrom and diverging outwardly at an angle, a socket seated in the V-shaped opening between the ears on the upright, a staple-driver mounted to slide on the arm and arranged to bear against the socket to hold it in place between the ears 30 thereof, a knob at the upper end of the driver, and a spring pocketed in the socket and acting against the knob to maintain the driver in raised position.

3. In a stapling-machine, the combination 40 of a base, an arm mounted above the base and provided with parallel spaced-apart uprights at its end, said uprights having forwardly extending ears provided with opposite vertical guideways, a staple-driver slid- 45 able on said guideways, a knob fastened to the upper end of the driver, a socket fitted between the uprights and provided with a flange seated against their upper edges to hold it in place thereon, and a spring pock- 50 eted in the socket to bear against the knob to maintain the driver in raised position.

4. In a stapling-machine, the combination 55 of a base, an arm mounted above the base and provided with spaced-apart uprights having ears extending forwardly therefrom and bent around at their ends to form opposite vertical guideways, a staple-driver slidably mounted on said guideways, a socket held between the ears with the driver bearing against its side to retain it in place, and a spring pocketed in said socket and adapted to act on the driver to maintain it in raised position.

5. In a stapling-machine, the combination 60 of a base, an arm mounted above the base

and having spaced-apart uprights formed with ears extending forwardly therefrom and bent around at the ends to provide opposite vertical guideways, a staple-driver having grooved edges adapted to slide on 70 said guideways, and a knob having a support fastened to the front of the driver with wings extending from the sides thereof to overlap the guideways to retain the driver in place thereon.

6. In a stapling-machine, the combination of a base, an arm mounted above the base and having spaced-apart uprights formed with ears extending forwardly therefrom and bent around at the ends to provide opposite vertical guideways, a staple-driver having grooved edges adapted to slide on 80 said guideways, a knob having a support fastened to the front of the driver and formed with extensions overlapping the guideways, and lugs at the bottom of the support bent around to engage the lower edges of the ears on the uprights to limit the upward sliding movement of the driver.

7. In a stapling-machine, the combination 85 of a base, an arm mounted above the base and provided with vertical guideways, a driver slidable on said guideways, and a knob for operating the driver, said knob constructed of sheet-metal with a flanged 90 top having an extension bent inwardly and then downwardly to abut the face of the driver with wings bent around from the sides thereof and extended upwardly beneath the top of the knob to provide a reinforcement therefor.

8. In a stapling-machine, the combination 95 of a base, an arm mounted above the base, a staple-driver slidably mounted on the arm, and a knob constructed of sheet-metal with 100 a substantially flat top formed with an extension bent inwardly from its edge and then downwardly in a front plate adapted to overlie the face of the driver to be fastened thereto and side wings bent at right- 105 angles to the front plate and extended upwardly in arms abutting the underside of the knob to reinforce the structure.

9. In a stapling-machine, the combination 110 of a base, a staple-carrying arm comprising opposite sheet-metal side-plates provided with inwardly projecting flanges on their upper edges, and a hollow core arranged within the arm in spaced-apart relation to its walls and upper flanges to adapt it to 115 receive the staples in straddled relation thereon and beneath the flanges on the side-plates which retain them within the staple-carrying arm.

10. In a stapling-machine, the combination 120 of a base, a staple-carrying arm comprising opposite sheet-metal side-plates provided with inwardly projecting flanges at the top, a hollow core arranged within the arm in spaced-apart relation to its inner 125

130

walls, and a staple-pusher slidable on the core beneath the side flanges on the arm which hold it in place on the staple-carrying arm.

11. In a stapling-machine, the combination of a base, a staple-carrying arm comprising opposite sheet-metal side-plates provided with inwardly projecting flanges at the top, a hollow core arranged within the 10 arm in spaced relation to its sides, and a staple-pusher having runners straddling the core to adapt it to slide thereon beneath the flanges on the side-plates which hold it in place on the staple-carrying arm.

12. In a stapling-machine, the combination of a staple-magazine having opposite side-plates formed with notches in their edges, a staple-pusher slidable on the magazine, a flat spring attached at one end to the 20 pusher and having its opposite end wound into a volute coil, and a support for the spring comprising a hub extending axially through the coil with the end of the latter secured thereto and the ends of the hub engaged with the notches in the side-plates of the magazine.

13. In a stapling-machine, the combination of a staple-magazine having opposite uprights provided with stepped notches in 30 their edges, a staple-pusher on the magazine, a volute spring connected to operate the pusher, and means for supporting said spring on the magazine comprising a tubular hub extending axially through the spring 35 and provided with an opening in its side and an inturned portion under which the end of the coil is secured, said hub having a narrowed portion adapted to be inserted between the sides of the uprights on the

magazine and shoulders engaging the 40 notches thereof to retain the hub in position while holding it from turning.

14. In a stapling-machine, the combination of a base, a staple-carrying arm, a pivot-pin on which the arm is hinged to the base, 45 and a flat spring secured to the base and extending across the pivot-pin with its outer end acting against the end of the arm to maintain the latter normally raised in tilted position above the base.

15. In a stapling-machine, the combination of a base provided with opposite hinge-ears, a hollow arm arranged between said ears, a pivot-pin extending through the ears and the sides of the arm and provided with 55 a groove on its side, and a flat spring secured at one end to the base and extending upwardly across the pivot-pin with its edges engaging the sides of the groove therein to hold the pin in place, the outer end of said 60 spring being arranged to act on the arm to maintain it in raised position above the base.

16. In a stapling-machine, the combination of a base provided with opposite hinge-ears, a hollow arm comprising spaced-apart 65 side-plates arranged between the hinge-ears, rivets for holding the side-plates in spaced-apart relation, a pivot-pin extending through the side-plates and hinge-ears, and a flat spring anchored at one end to the base and 70 extending upwardly between the sides of the arm to bear against the pivot-pin and one of the rivets to cause it to be flexed to normally maintain the arm in raised position above the base.

75 In testimony whereof I affix my signature.

ARTHUR H. MAYNARD.
